(57) **CLAIM**

I claim the ornamental design for an elongate decoration-hanging tool, as shown and described.

DESCRIPTION

FIG. 1 is an exploded perspective view of an elongate decoration-hanging tool showing my new design;

FIG. 2 is an exploded front elevational view thereof;

FIG. 3 is an exploded rear elevational view thereof;

FIG. 4 is a top plan view thereof;

FIG. 5 is a bottom plan view thereof;

FIG. 6 is an exploded side elevational view thereof;

FIG. 7 is an exploded elevational view of the opposing side thereof; and,

FIG. 8 is a reduced perspective view showing the elongate decoration-hanging tool in use; the broken lines depict environmental structure for illustrative purposes only and form no part of the claimed design.
